UNITED STATES PATENT OFFICE.

THOMAS RICHARDS, OF RENFREW, ONTARIO, CANADA.

RAIL-FASTENING.

994,872.

Specification of Letters Patent. Patented June 13, 1911.

Application filed March 16, 1911. Serial No. 614,901.

To all whom it may concern:

Be it known that I, THOMAS RICHARDS, of Renfrew, in the township of Horton, county of Renfrew, Province of Ontario, Dominion 5 of Canada, have invented certain new and useful Improvements in Rail-Fastenings, of which the following is a specification.

My invention relates to improvements in rail fastenings and supports and the objects 10 of my invention are to provide means for preventing the spreading or drawing closer together of the rails or the canting thereof and such means as will firmly and effectually hold the two opposite rails in their 15 proper relative position and to further operate to prevent the tilting of the individual rail, and thus prevent many railway accidents, lengthen the life of the ties and reduce the labor of the section men.

20 My improved fastening consists essentially of binding members provided with chair members which lock the rails securely on said binding members while novel means are provided for adjusting the position of 25 said binding members relative to each other and for securely locking the same in their adjusted position all of which is herein more particularly described in the accompanying drawings and specification.

30 In the drawings like letters of reference indicate corresponding parts.

In said drawings, Figure 1 represents a perspective view of my improved fastening. Fig. 2 is a longitudinal sectional view of 35 the same. Fig. 3 is a side view of one of the binding members employed in which the inside surface of the binding member is shown. Fig. 4 is a horizontal sectional view of my improved rail brace. Fig. 5 is a sectional detail on the line 2—2, Fig. 1. Fig. 40 6 is a sectional view on the line 3—3, Fig. 1. Fig. 7 is a perspective view of a block used in the device.

45 Referring to said drawings, A represents the rail fastening formed of suitable material such as iron or steel and consists of two adjacent binding members 10 and 11 provided at their outer extremities with chair members 12 which are shaped to fit snugly 50 against the outer surfaces of the rails and prevent the same from spreading outwardly, while in order to lock said chair members 12 securely on the binding members 10 and 11 tongues 13^a are provided in-

tegral with the chair members which lock in 55 suitable dove-tail slots 14 provided in the binding members. If desired, tightening wedges might be inserted between the tongue and groove.

Any inward displacement of the rails is 60 prevented by the provision of the projections 13 integral with the binding members 10 and 11, said projections being shaped to fit tightly against the inside base plates of the rails. The binding members 10 and 11 65 are secured together at their overlapping portions by means of bolts 15 and in order to adjust the position of the binding members relatively to each other, slots 16 are provided in the member 11 in which the 70 bolts may slide.

The binding member 10 is provided with a downwardly tapering groove 17 which receives an upwardly tapered projection 18 formed integral with the binding member 11 so that when the two binding members 10 and 11 are placed together the projection 18 divides the groove 17 into two tapered slots 19 and 20 into which a drop pin 21 and a 75 regulating block 22 are engaged to fit. The block 22 is adapted to be inserted in position before the two binding members are clamped together and is retained in position by means of a tongue 22^a formed thereon 80 adapted to take into a transverse groove 22^b formed in the bottom of the groove 17. The pin 21 is adapted to be driven in to fill up the space and tighten the members 85 in a longitudinal direction.

It may be mentioned that the regulating block 22 and drop pin 21 may be made in 90 different sizes so as to adapt the device to different sizes of rails.

To prevent any downward displacement between the binding members, a longitudinally extending tongue 23 is provided on each member 10 and 11, which locks in a 95 corresponding groove 24 similarly provided.

It will be readily seen that I have devised an extremely simple and effective device for 100 accomplishing the purposes hereinbefore set forth.

As many changes could be made in the 105 above construction and many apparently widely different embodiments of my invention, within the scope of the claims, constructed without departing from the spirit or scope thereof, it is intended that all mat-

ter contained in the accompanying specification and drawings shall be interpreted as illustrative and not in a limiting sense.

What I claim as my invention is:

- 5 1. A rail fastening for rail-road rails comprising adjacent binding members provided with slots, chair members adapted to lock against the outside surface of the rails provided with tongues adapted to lock in said 10 slots, means for adjusting the position of the binding members to each other and means for locking the same in adjusted position.
- 15 2. A rail support for rail-road rails comprising adjacent binding members provided with projections adapted to lock against the inside surface of the rails and with slots, chair members adapted to lock against the outside surface of the rails provided with 20 tongues adapted to lock in said slots, means for adjusting the position of the binding members relatively to each other and means for locking the same in adjusted position.
- 25 3. A rail support for rail-road rails comprising two adjacent binding members provided with slots, chair members adapted to lock against the outside surface of the rails, provided with tongues adapted to lock in said slots, one of said binding members provided with a slot, a bolt located in the other binding member adapted to project through said slot and means for locking said bolt in the slot.
- 35 4. A rail support for rail-road rails comprising two adjacent binding members provided with projections adapted to lock against the inside surface of the rails and with slots, chair members adapted to lock against the outside surfaces of the rails provided with tongues adapted to lock in said 40 slots, means for adjusting the position of

the binding members relative to each other, means for securing said members in adjusted position, one of said members being provided with a downwardly tapered groove, 45 the other with a projection adapted to protrude into said groove and divide the same into tapered slots and a regulating block and pin adapted to fit said tapered slots.

5. A rail fastening for rail-road rails comprising two adjacent binding members provided with projections adapted to lock against the inside surface of the rails and with slots, chair members adapted to lock against the outer surface of the rails provided with tongues adapted to lock in said 55 slots, means for adjusting the position of said binding members, relative to each other, means for locking the same in adjusted position, one of said binding members being provided with a horizontally extending tongue and the other binding member with a groove adapted to receive said tongue.

6. A rail fastening comprising adjacent binding members one of which has a groove and the other a projection fitting therein and of less width than the same, said groove having a transverse groove formed across the bottom thereof, a regulating block extending between one side of the projection 70 and the side of the first mentioned groove and having a tongue to fit the transverse groove and a drop pin extending between the opposite side of the projection and the 75 side of the groove.

In witness whereof I have hereunto set my hand in the presence of two witnesses.

THOMAS RICHARDS.
